UNITED STATES PATENT OFFICE.

GUSTAV SCHLATTER, OF STEINACH, SWITZERLAND, ASSIGNOR TO FIRMA ADOLPHE SAURER, OF ARBON, SWITZERLAND, A FIRM OF SWITZERLAND.

TOWER-WAGON.

1,337,487.

Specification of Letters Patent. Patented Apr. 20, 1920.

Application filed September 13, 1919. Serial No. 323,666.

To all whom it may concern:

Be it known that I, GUSTAV SCHLATTER, a citizen of the Swiss Republic, residing in Steinach, Switzerland, have invented certain new and useful Improvements in Tower-Wagons, of which the following is a specification, reference being had to the accompanying drawings, forming a part hereof.

This invention relates to tower wagons such as are commonly employed in the repair of overhead electric wiring. Such wagons usually comprise a motor vehicle and a platform movably supported upon the same so that it can be raised and lowered to furnish a suitable support for the workmen who are engaged in repairing the wiring. The present invention is concerned particularly with the means for raising and lowering the working platform, the means for locking the same in elevated position, and the means for rotating the platform. The invention will be more fully explained hereinafter with reference to the accompanying drawings in which it is illustrated, and in which—

Figure 1 is an outline view in elevation showing the motor vehicle equipped with the movable working platform.

Figs. 2 and 3 are views, partly diagrammatic and partly in vertical section, showing the means for supporting, raising and lowering the platform and for locking it in elevated position.

Fig. 4 is a detail view of the locking device.

Fig. 5 is a detail view in elevation illustrating particularly the means for rotating the platform.

Fig. 6 is a detail view of the same in vertical section.

Fig. 7 is a detail view in horizontal section on the plane indicated by the broken line 7—7 of Fig. 6, looking upward.

Figs. 8 and 9 are detail views of the back pressure or check valve and the means for short-circuiting the pump.

The motor vehicle may be constructed in any usual or suitable manner, having a suitable chassis frame *a*, a body *b*, a motor located at *c*, driving wheels *d* and front steering wheels *d'*.

The movable platform *e*, provided with a guard railing *e'*, is mounted rotatably at the upper end of the tube *f*, which telescopes within a tubular standard or pillar *g*, suit-

ably supported upon the chassis frame *a*. The details of the means for supporting the platform rotatably, for rotating the platform, and for locking it in rotated position are clearly shown in Figs. 5, 6 and 60 7 and will be described more particularly hereinafter. Such details are omitted from Figs. 2 and 3 for the sake of clearness.

The supporting and extensible tube *f* has a free working fit within the tubular standard *g* and has formed with it or secured to it and extended upwardly from its lower end, a cylinder *f'*, (closed at its upper end) within which is received, with a close working fit, like a piston, a tube *g'*. The latter 70 is open at its upper end and is provided, a short distance below its open upper end, with a safety or relief port *g*², which is uncovered by the cylinder *f'* when the piston has been raised to its highest point, so 75 that the pressure oil which is delivered to the piston tube *g'* may escape and so cease to raise the platform higher. The lower part of the chamber within the tubular standard or pillar *g* forms a reservoir for 80 the pressure oil and at *g*³ may be provided a relief or safety port to permit the escape of any excess of pressure oil.

The pressure oil is delivered to the tubular piston *g'* by a pump *h* which may be 85 driven in any convenient manner from the motor of the vehicle under the control of the driver. The pump is connected on the discharge side by a pipe *h'* in which is interposed at a convenient point a back pressure or check valve *h*², which permits a free flow of oil from the pump to the cylinder *g'* when the platform is being raised, and a restricted flow from the cylinder back to the pump when the platform is being lowered. The reservoir in the bottom of the tubular pillar or standard *g* is connected by a pipe *h*³ with the inlet or suction side of the pump *h*.

It will be understood that when the working platform *e* is to be elevated, the pressure oil, drawn from the reservoir in the bottom of the standard *g*, is forced by the pump *h* into the tubular piston *g'*, whereby the platform is elevated, and that when 100 the platform is to be lowered, the pump is stopped or short-circuited and, under the weight of the platform and its connections, the oil is forced backward through the pipe *h'*, valve *h*² and pump *h*, the movement of 105 110

the oil backward being restricted by the valve at h^2 so that the descent of the platform is gradual.

- By stopping or short-circuiting the pump 5 the elevation of the platform can be stopped at any desired point and in order to overcome the effect of leakage and to make it unnecessary to continue the operation of the pump, there is provided a mechanical locking device to retain the platform in elevated 10 position, which locking device is so constructed that it cannot be released accidentally or through inattention or mistake. As shown in Figs. 2 and 3, and more in detail in Fig. 4, the tube f is provided at intervals with openings f^2 and the tubular standard g is provided near its top with a locking bolt k which is pressed normally forward by a spring k' , in a suitable casing 15 k^2 , to enter one of the holes f^2 and engage the extension tube f and may be withdrawn, to release the extension tube f , by a hand lever k^3 mounted on the standard g . The bolt k is beveled on its under side, as at h^4 , 20 so that the bolt shall be thrust back by the extension tube f as it rises, and is provided also with a lip k^5 which prevents the withdrawal of the bolt and the release of the platform until the pump has been started and the platform raised slightly so as to permit the bolt to be withdrawn. This device, the operation of which will be understood readily, prevents any accidental or unintended lowering of the platform. The 25 bolt k , by its engagement with the extension tube f , prevents rotation of the latter within the standard g .
- The working platform e is secured to a suitable casting e^2 (see particularly Fig. 40 6) which has bolted to it the downwardly extended sleeve e^3 . The latter has a working fit within a flanged bushing e^4 which is received within the hub m' of a gear m . The head or casting e^2 is rotatable with respect to the gear m which is held from rotation through the engagement of its hub m' with a sleeve m^2 which is provided with longitudinal ribs m^3 for engagement with vertical grooves m^4 formed in a sleeve m^5 , 45 the latter being fitted tightly in the upper end of the extension tube f . The gear m is formed with gear teeth m^6 and on its under side, for a purpose to be explained, with peripheral notches m^7 . Rotatably mounted 50 in a suitable bearing n' , carried by the head or casting e^2 , is a spindle n formed near its lower end with gear teeth n^2 , at its lower end with a locking circular flange n^3 , and at its upper end with a head n^4 . The spindle 55 is shouldered at the head n^4 and in the bearing n' is a spiral spring n^5 which normally presses the spindle upward, holding the circular flange n^3 in one of the notches, m^7 , of the gear m and thereby locking the platform 60 against rotation with respect to the

gear m . The driving pinion formed by the teeth n^2 is always in engagement with the gear teeth m^6 of the gear m and when a suitable key o is inserted in the head n^4 of the spindle n from above and is pressed down, the spindle n is moved downward against the spring n^5 sufficiently to move the flange n^3 out of engagement with the locking notch in the gear m . If the key is then rotated by means of its handle o' the platform 70 will be rotated, the pinion traveling with the platform about the stationary gear m with the teeth m^6 of which it is in engagement. After the rotation of the platform has been started no further pressure downward upon the key o is required as the flange n^3 will then bear against the under side 75 of the gear, but when the next notch m^7 is brought into line with the spindle, the spring n^5 will lift the spindle and bring the flange n^3 into engagement with the notch, thereby again locking the platform against rotation. The key o can at any time be withdrawn and dropped into a socket 80 provided therefor in the platform, thereby 85 leaving the platform unobstructed for the workmen.

It will be understood that various changes in details of construction can be made to suit different conditions of use or the convenience of the manufacturer and that the invention, therefore, is not limited to the precise details of construction shown and described herein.

I claim as my invention:

1. In an apparatus of the character described, the combination of a tubular standard, an extension member having a cylinder with its upper end closed, a fixed tubular piston-like member fitting within the cylinder and having its upper end open, and means to supply liquid under pressure to said tubular piston-like member.

2. In an apparatus of the character described, the combination of a tubular standard, an extension member having a cylinder with its upper end closed, a fixed tubular piston-like member fitting within the cylinder and having its upper end open, and means to supply liquid under pressure to said tubular piston-like member, the tubular piston-like member having a relief opening below its upper end to limit the upward movement.

3. In an apparatus of the character described, the combination of a tubular standard, forming at its lower end a liquid reservoir, an extension member movable freely within the standard and having a central cylinder at its upper end, a tubular piston-like member fixed in the lower end of the standard and having a close fit within the cylinder and an open, upper end, a pump, a connection from the reservoir to the intake side of the pump and a connection from the

discharge side of the pump to the tubular piston-like member.

4. In an apparatus of the character described, the combination of a tubular standard, forming at its lower end a liquid reservoir, an extension member movable freely within the standard and having a central cylinder at its upper end, a tubular piston-like member fixed in the lower end of the standard and having a close fit within the cylinder and an open, upper end, a pump, a connection from the reservoir to the intake side of the pump, a connection from the discharge side of the pump to the tubular piston-like member and a restricted back pressure valve in the connection between the pump and the tubular piston-like member.

5. In an apparatus of the character described, the combination of a tubular standard, an extension member, hydraulic means to raise the extension member and a bolt mounted on the standard and adapted to engage the extension member and having a lip on its upper side to be engaged by the extension member to prevent the withdrawal of the bolt until the extension member is slightly raised, and means to withdraw the bolt.

6. In an apparatus of the character de-

scribed, the combination of a tubular standard, an extension member movable vertically within the standard, means to hold the same from rotation, hydraulic means to elevate the extension member and a working platform rotatably mounted at the upper end of the extension member, a gear fixed on the extension member and a driving pinion carried by the platform and engaging the fixed gear.

7. In an apparatus of the character described, the combination of a tubular standard, an extension member movable vertically within the standard, means to hold the same from rotation, hydraulic means to elevate the extension member and a working platform rotatably mounted at the upper end of the extension member, a gear fixed on the extension member and a driving pinion carried by the platform and engaging the fixed gear, the fixed gear being provided with locking notches and the driving pinion being movable axially and provided with a locking disk to be moved into or out of engagement with the fixed gear.

This specification signed this 30 day of July, A. D. 1919.

GUSTAV SCHLATTER.
